[57] CLAIM

The ornamental design for a front panel for a two-way mobile radio, as shown and described.

DESCRIPTION

FIG. 1 is a top, front and left side perspective view of a front panel for a two-way mobile radio showing my new design;

FIG. 2 is a front elevational view thereof;

FIG. 3 is a top plan view thereof;

FIG. 4 is a right side elevational view thereof;

FIG. 5 is a bottom plan view thereof; and

FIG. 6 is a left side elevational view thereof.

The broken-line showing of the two-way mobile radio is for illustrative purposes only and forms no part of the claimed design.
